(57) **CLAIM**

The ornamental design for a pump holding clip with battery charging capability as shown and described.

DESCRIPTION

FIG. 1 is a top perspective view of a pump holding clip with battery charging capability;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view; and,

FIG. 8 is a bottom perspective view thereof.

The broken lines shown in the drawings depict portions of the pump holding clip with battery charging capability, and form no part of the claimed design.
